DRAFT RIGGING

Donald S. Barrows, Rochester, N. Y., assignor to
The Symington Company, New York, N. Y., a
corporation of Maryland

Application June 20, 1928, Serial No. 287,013

12 Claims. (Cl. 213—50)

This invention relates to draft rigging and more particularly to a form thereof adapted for employment with a swivel butt coupler.

The principal object of my invention, generally considered, is to provide a draft rigging with a swivel butt coupler and involving a special form of striking casting and sill tie member, front draft lugs with webs extending from one sill to the other and an improved form of backstop. 10 Another object of my invention is to provide a striking casting and front draft lug assembly involving a combined casting connected to the associated end sill and formed with rearward extensions connected to the outer surfaces of the 15 associated draft sills of a car and draft lug castings comprising a portion above the draft key receiving slots in the sills and extending between said sills and forwardly to engage the end sill, the lower portion extending between the sills and 20 forwardly to the sill tie portion and serving as a coupler guide member.

A further object of my invention is to provide a car underframe involving spaced draft sills connected by top and bottom cover plates and a 25 backstop and center filler casting, said lower cover plate being coped adjacent the forward portion thereof between the sills so as not to interfere with associated cushioning mechanism, a center plate being connected to said sills below 30 said cover plate and extended forwardly beneath said cushioning mechanism.

A still further object of my invention is to provide a swivel butt coupler in which the shank is of uniform dimensions or outline from the 25 rear or swiveling portion thereof to the coupler head whereby it may be readily inserted and withdrawn from an associated striking and sill tie casting without the employment of removable striking or coupler supporting blocks or filler 40 pieces.

Other objects and advantages of the invention relating to the particular arrangement and construction of the various parts will become apparent as the description proceeds.

Referring to the drawings illustrating my invention, the scope whereof is defined by the appended claims.

Figure 1 is a longitudinal vertical sectional view of a car underframe showing one form of my draft rigging.

Figure 2 is a partial plan and partial horizontal sectional view of the underframe and rigging shown in Figure 1.

Figure 3 is a fragmentary sectional view cor-

responding to Figure 1 with the coupler and cushioning mechanism removed.

Figure 4 is a partial front elevation and partial transverse sectional view on the line 4—4 of Figure 1, looking in the direction of the arrows. 35

Figure 5 is a transverse sectional view on the line 5—5 of Figure 1, looking in the direction of the arrows.

Figure 6 is a longitudinal sectional view on an enlarged scale of the swivel butt coupler stem 65 shown in Figure 1.

Figure 7 is a transverse sectional view on the line 7—7 of Figure 6, looking in the direction of the arrows.

Figure 8 is a plan of the lower front lug 70 casting.

Figure 9 is a front elevation of the casting shown in Figure 8.

Referring to the drawings in detail, like parts being designated by like reference characters, 75 there is shown a draft rigging embodied in a car underframe involving center or draft sills 1 connected at their ends to an end sill 2 and preferably formed with vertical webs 3 and outstanding flanges 4, to the latter of which is connected 80 the top cover plate 5 and a bottom cover plate 6.

A combined casting 7, involving a striking casting portion 8, a sill tie or coupler carrier portion 9, and side portions 10 extending between the striking and sill tie portions, is connected to the 85 end sill 2 and provided with side extensions or webs 11 connected to the outer sides of the draft sill web 3, as by means of rivets 12, shown most clearly in Figure 3. The combined casting 7 is desirably formed with a rearwardly extending 90 upper web or flange 13 engaging the upper face of the top cover plate 5, said cover plate being thereby received at its outer edge between said flange and the end sill upper flange 14 and connected thereto in any desired manner. 95

The webs 3 of the draft sills 1 are slotted, as indicated at 15, for receiving the draft key 16 which serves to support the associated coupler stem 17 and connect it to the yoke 18. In order not to interfere with the slot 15 the rearwardly extending webs 11 are bifurcated or formed as upper and lower portions 19 and 20, the adjacent edges of said portions being preferably beaded or ribbed inwardly, as indicated at 21, said beading extending over the edges of the slotted portions 15 in the sills and connected at the forward portions thereof to form in effect the forward portions of cheek plates, said ribbed edges 21 providing surfaces of increased area for supporting the draft key 16. 100

105

110

Connected to the inner faces or sides of the sill webs 3 are draft lugs formed as an upper casting 22 and a lower casting 23. The upper casting 22 is formed with side webs 24 connected to the webs 3 of the sills, a horizontal transverse web 25 integrally connecting the side webs 24 and extending between the sills and above the associated coupler 17, and transverse draft lug portions 26, normally engaged by the front follower 27 of an associated cushioning mechanism 28. Although the cushioning mechanism illustrated is a friction draft gear, it is obvious that I do not wish to be limited to this showing.

At its forward end the web 25 is flanged, as indicated at 29, and connected to the inner face of the end sill 2, whereby said end sill is received between the combined casting 7 and the upper draft lug and tie member 22. The lug portions 26 are desirably braced with respect to the web 25 by upper triangular gusset portions 30 and lower preferably tapering ribs 31 and triangular gusset bracing portions 32 are also desirably provided between the lower ends of the lug portions 26 and the webs 24 of the casting, which are preferably connected to the sill webs 3 by rivets 33. The webs 24 are extended to approximately supplement the rearwardly extending portions 11 on the combined casting 7, as shown most clearly in Figure 3, so that the sills are adequately strengthened, said web portions 24 being on the inside thereof and the web portions 11 on the outside. As in the case of the web portions 11, the edges of the webs 24 are preferably beaded or ribbed around the slotted portions 15 in the sills, as indicated at 34, thereby increasing the bearing area for the key 16 and forming in effect supplemental cheek plate portions. The lower lug casting 23 is similarly formed in that it comprises a transverse web 35 connecting the lug portions and sills and forming an intermediate sill tie and coupler guiding plate.

The forward edge of said web 35 is preferably flanged downwardly adjacent the sill tie portion 9, as indicated at 36 and the rearward portion is flanged downwardly, as indicated at 37, forming a lug portion for engagement with the front follower 27. Said lug portion is preferably braced with respect to the web 36 by triangular gussets 38. As with respect to the upper lug portion, the upper edges of the side webs 39 are beaded or ribbed outwardly over the edges of the slotted portions 15 in the sills, as indicated at 40. The upper edges of the lug portions 37 are preferably strengthened by triangular gusset portions 41 between said lug portions and the webs 39. Below the lower flanges 4 of the sills 1 the web 35 is downwardly offset, as indicated at 42, to directly underlie said flanges for connection therewith by rivets 43. Said offset portions 42 are suitably reinforced by extending the lug web portion 37 outward to the ends of said web portions 42, as indicated most clearly in Figure 4.

The coupler 17 is of the swivel butt type, for example, such as described and claimed in my Patent 1,431,717, dated October 10, 1922. The rear end of the stem proper is therefore formed with a pair of spaced flanges or webs 44 embraced by a swivel block 45 which is formed with flanges or webs 46, which are interspaced so as to lie on opposite sides of the webs 44 and provide bearing pockets 47 therebetween for engaging correspondingly curved edges 48 on the flanges or webs 44 for swiveling engagement therebetween. The swivel block and coupler stem are connected for pivotal movement therebetween by a vertical pin

or pintle 49, which is so positioned that it is cut into by the key 16, as indicated at 50, whereby when the parts are assembled the pin or pintle 49 is retained in proper position by said key.

In order, however, to avoid disarrangement of the parts when the key 16 is not in place, I preferably hold the pin 49 in temporary assembled relation with the swivel block and coupler stem by forming cuts in the ends of said pin, as indicated at 51, and spreading said cuts to form in effect upset ends on said pin and prevent undesired removal or loss in a manner similar to that shown in Figures 4 and 6 of my Patent 1,431,717, previously referred to. The edges of the webs 44 and 46, as well as the corresponding pocket portions, are preferably coaxial with the pin 49 to provide for proper swiveling motion between the parts.

It is well known that a swivel butt coupler of the type described is generally larger in transverse dimensions than a rigid shank coupler and the portion immediately adjacent the swivel block has generally been made larger in such dimensions than the coupler stem between the head of the coupler and the end thereof. Such a construction, while necessitating an increased opening in the striking casting for receiving the swivel block and enlarged butt of the stem, has made it generally desirable or necessary to provide means for closing the opening to some extent after insertion of the swivel block and butt of the coupler, whereby the clearance between the stem and striking casting would not be too great. This has been accomplished, for example, by having removable wear or filler blocks below, above, or below and above said stem which are removed when the coupler butt is being inserted or withdrawn and are held in position in any desired manner when the coupler is in position.

In accordance with my present invention I have enlarged the stem of the coupler between the butt and head thereof so that the vertical and horizontal transverse dimensions are uniform throughout the length of the stem and swivel block whereby upon designing the striking casting for normal clearance with respect to the butt and swivel block said normal clearance is maintained when the coupler is in normal position as indicated, for example, in Figure 1. This result has been accomplished in the present embodiment by sloping the lower web 52 downwardly and rearwardly, as indicated particularly in Figure 6, to the lowermost portion of the coupler stem, as indicated at 53, where it overlies the sill tie or coupler carrier portion 9 of the striking casting, a wear plate being desirably provided between said coupler and sill tie portion. Rearwardly of the horizontal portion 53 the lower web of the coupler is sloped upwardly, as indicated at 54, to join with the lower curved butt flange or web 44. The upper web 55 of the coupler stem is desirably continued straight forwardly from the offset portion 56 forming a shoulder for engagement with the upper web 46 of the swivel block 45, said portion 55, however, being formed as an upward convolution of reduced width above the stem 17 in the coupler and forming in effect a spacing rib or corrugation for avoiding abnormal clearance with respect to the striking portion 8 of the casting 7, and leaving portions of the upper wall on either side, which unite with the side walls, substantially aligned with the upper flange 44. The lower outline of the coupler is maintained straight and filled out by ribs or webs 57, the lower edges of which are flush with the lower surface of the web portion 53.

150

The yoke 18, which is connected to the coupler 17 by means of the key 16, extends rearwardly around the associated cushioning mechanism 28 and normally abuts the front face 58 of the combined backstop and center filler casting 59. The cushioning mechanism 28 is supported by the carrier iron 60, the ends of which are in turn connected to the outstanding lower flanges 4 of the sills by means of bolts 61 and nuts 62 or any

10 other desired connecting means. Undesired upward movement or displacement of the cushioning mechanism is prevented by an upper tie member 63 connected to the inner surfaces of the sill webs by rivets or the like 64. The rear or U-shaped portion of the yoke 18 is desirably supported by angular clips 65, the vertical flanges of which are desirably connected to the sills by countersunk rivets 66 or the like and the horizontal flanges of which underlie the adjacent portions

15 of the yoke. The front portions of the yoke are not only supported by the key 16 but are held in place by being snugly received between the gussets 32 and 41, as shown most clearly in Figure 4.

20 The backstop 59 has a lower wall or web 67 which is directly supported on the bottom cover plate 6 and connected beneath said cover plate is the center plate or casting 68. The height of the draft gear or cushioning mechanism 28 is such in the present embodiment that the cover plate 6 is cut away, as indicated at 69, to avoid interference therewith, the center plate 68, however, underlying the adjacent end of said gear, as illustrated particularly in Figure 1. The center plate 68 is formed, as is usual, with a king pin aperture 70 and the bottom cover plate 6 and the striking casting 59 are formed with registering apertures 71 and 72, respectively serving as continuations of the king pin aperture 70.

25 In order to strengthen the backstop casting 59, the apertured portion 72 is formed as a hollow cylinder extending the full height of the casting between the lower web or floor 67 and the upper web or top 73, said top 73, however, not being quite as high as the upper edges of the side or connecting walls 74, thereby providing areas above said top for receiving rivets 75 for connecting said casting to the sills of the car. The upper wall 73 does not extend as far back as the 30 lower wall 67 in the center thereof but the sides are preferably flared outwardly and rearwardly, as indicated at 76, to finally merge into the side walls 74. The front or striking wall 58 of the casting is provided with flaring extensions 77 forming 35 in effect gussets between the extended sides 74 of the casting and the top or roof web 73.

In the present embodiment a plurality of horizontal webs 78 are provided between the top and bottom webs, which webs extend from the front web around the hollow cylindrical portion 72 and rearwardly to slightly beyond the rear edge of the bottom web 67, where they are flanged, as indicated at 79. An intermediate vertical web 80 is also provided extending from approximately 40 the center of the striking web 58 to the flanged edges of the webs 78 and tapering from said flanged edges upwardly and downwardly to the rear edges of the webs 73 and 67, respectively. For bracing the longitudinally extending webs intermediate the ends thereof transverse webs 81 are provided extending inwardly from the sides 45 only partially to the center of the casting, leading openings between all of the webs from the rear of the casting for core removal. The 50 side webs 74 are preferably extended forwardly

of the front or buffing web 58 to provide riveting areas 82.

In the present embodiment the bolster involves pressed plates or transoms 83, the forward one of which has its web preferably in line with the front web 58 of the striking casting and the rearward of which has its web preferably in line with the webs 81 of the casting, said front transom being preferably connected to the casting by common rivets extending through the side extensions 82, the sill webs and the adjacent flanged portions 84 of the transoms. The rear bolster transoms 83 may be connected to the sills and striking casting in a similar manner.

55 From the foregoing description of my invention, taken in connection with the accompanying drawings, it will be seen that I have provided an improved rigging construction in which front draft lugs are formed as integral ties above and below the draft key receiving slots in the sills. The backstop and center filler casting is of special construction providing for great strength without undue weight and the bottom sill cover plate, which underlies said backstop casting, is coped to permit the employment of a draft gear of 100 maximum height. The coupler desirably employed is of the swivel butt type and the pintle or pivot pin thereof is temporarily retained in position by, in effect upsetting the ends thereof but when in place the lower draft lug cross tie 105 is located so as to avoid loss of the pin in any event. The shank of the swivel butt coupler is formed of uniform dimensions throughout to avoid the necessity for filler castings above or below in the striking casting.

110 Having thus described my invention, I claim:

1. In railway draft rigging in combination with associated draft sills having slots therein for the reception of a draft key, a combined casting functioning as a striking casting and sill tie with 115 rearwardly extending portions notched to register with said slots and serving as the forward portions of cheek plates, and front draft lugs connected to said sills and formed with portions connected to said sills and serving as extensions of those parts of the rearwardly extending portions above and below the notches, thereby 120 reinforcing the sills at the slotted portions and supplementing the cheek plate portions and with webs extending from one sill to the other.

2. In railway draft rigging, in combination with draft sills, an end sill, a combined casting connected to said end sill and functioning as a striking casting and sill tie member with rearwardly extending portions connected to the draft sills and functioning as the forward portions of cheek plates, and front draft lugs connected to said sills and formed with portions supplementing the cheek plate portions and with webs extending 125 from one sill to the other, the upper web being forwardly extended to the end sill.

3. In railway draft rigging, in combination with an associated end sill and draft sills, a striking casting formed with an upper striking portion, a lower coupler supporting portion and side portions with rearward bifurcated extensions connected to the draft sills, said sills being slotted for receiving an associated draft key, said connected portions of the casting extending on either 130 side of said slots and functioning as partial cheek plates, and front draft lugs connected to said sills and engaging the webs thereof on opposite sides from the striking casting extensions and continued forwardly to supplement said extensions 135.

for reinforcing the sills, said lugs being formed as an integral casting above the slots in the sills with webs extending therebetween and forwardly to the end sill, an an integral casting below said 5 slots with a web extending between said sills.

4. In railway draft rigging, in combination with associated draft sills and an end sill, a combined casting connected to the end sill and functioning as a striking casting and sill tie member, with 10 rearwardly extending webs connected to the draft sills and an opening for receiving the butt of an associated coupler, front draft lugs connected to said sills and formed with webs connected to the draft sill webs above and below draft key receiving slots therein, and webs extending between the lug portions and adapted to overlie and underlie an associated coupler, the upper of said webs being connected to the end sill.

5. In railway draft rigging, in combination with 20 associated draft sills formed with slots for receiving an associated draft key, a combined casting functioning as a striking casting and sill tie with rearwardly extending portions connected to the outer sides of the sills and formed with rearwardly opening notches defined by beading extending into said slots and serving as the forward portions of cheek plates, and front draft lugs connected to the inner sides of said sills and formed with edge portions defined by beading 30 extending into said slots as continuations of the combined casting beading, and supplementing the cheek plate portions and with webs extending from one sill to the other.

6. In railway draft rigging, in combination with 35 draft sills, an end sill, a combined casting connected to the front face of said end sill and functioning as a striking casting and coupler carrier iron with rearwardly extending portions connected to the draft sills and functioning as the forward portions of cheek plates, and front draft lugs connected to said draft sills and formed with portions supplementing the cheek plate portions and with webs extending from one draft sill to the other, the upper web being forwardly extended 45 and connected to the rear face of the end sill and the lower web adapted to closely underlie an associated coupler.

7. In railway draft rigging, in combination with an associated end sill and draft sills, a combined 50 casting formed with an upper striking portion, a lower coupler supporting portion and side portions with rearward bifurcated extensions connected to the draft sills, said sills being slotted for receiving an associated draft key, said connected 55 portions of the casting extending on either side of said slots and functioning as partial cheek plates, and front draft lugs formed with side webs connected to said sills and engaging the webs thereof on opposite sides from the striking casting extensions and continued forwardly to supplement said 60 extensions for reinforcing the sills, said lugs being formed as an integral casting above the slots in the sills with webs extending therebetween and forwardly to the end sill, and an integral casting 65 below said slots with a web extending between said sills, the lug side webs being formed with inwardly extending reinforcing webs also serving as yoke guides.

8. In railway draft rigging, in combination with 70 associated draft sills formed with slots for receiving a draft key, a combined casting functioning as a striking casting and sill tie member, and formed with rearwardly extending webs connected to the outer sides of the sills and beaded inwardly over the sill edges at the slots, said casting having an

opening for receiving the butt of an associated coupler, front draft lugs connected to the inner sides of said sills and formed with webs connected to the sill webs above and below said draft key receiving slots therein, the edges of said webs above and below said slots being beaded outwardly over the sill edges at the slots, forming continuations of the combined casting beading, and webs extending between the lug portions and adapted to overlie and underlie an associated coupler. 80

9. A coupler stem comprising intermeshing pivotally connected members, a transversely extending coupler key slot formed in part in each of said members, the lower outline of said stem being straight from the extreme rear end to the coupler head and the upper outline thereof being straightened by an upward convolution in the stem portion forwardly of the pivotally connected butt portion, whereby said stem is insertable in a combined striking and coupler carrier casting with uniform clearance between all portions thereof and said casting. 90

10. In railway draft rigging, in combinaiton with draft sills and an associated end sill, a combined casting, apertured for receiving the stem 100 of an associated coupler, comprising an upper striking portion engaging the outer face of the end sill, a lower sill tie and coupler supporting portion, and rearwardly extending bifurcated side portions connected to the draft sills, said 105 sills being slotted for receiving an associated draft key, said bifurcated extensions engaging the outer surfaces of the sills and lying on either side of said slots to function as the forward portions of cheek plates, and front draft lugs connected to said sills and engaging the inner surfaces of the webs thereof, said draft lugs having side webs extended forwardly to supplement the side portions of the combined casting to function 110 as cheek plates for reinforcing said sills, said lugs being formed us upper and lower castings, the upper casting having a horizontal web extending between the sills and connecting the web portions thereof which are attached to said sills, said connecting portions extending forwardly to engage the inner face of the end sill, the lower edge of said connecting portion being disposed at approximately the level of the lower edge of the striking portion of the combined casting for guiding the stem of an associated coupler and 115 limiting upward movement thereof, the lower casting having a web portion extending between the sills and connecting the side portions thereof which are attached to said sills, the upper surface of said connecting portion lying slightly 120 below the level of the coupler carrier and sill tie member of the combined casting. 125

11. A coupler with a head and a stem having a pair of normally horizontal flanges extending from the rear portion thereof, a swivel block with three flanges extending forwardly therefrom and intercalated with the flanges on the stem, said flanges having registering apertures, a pivot pin extending through said apertures for connecting said stem and swivel block, said stem forwardly 130 of said flanges having top, bottom and side walls, said bottom wall sloping upwardly and rearwardly from an intermediate normally horizontal portion, the lower surface of which lies in the same plane as that of the swivel block, to join the 135 lower flange on said stem, and sloping upwardly and forwardly from said intermediate portion to the head, the portions of said stem beneath said sloping portions of the bottom wall being reinforced by gussets, the lower outlines of which 140

correspond with that of said lower wall for maintaining the bottom of the assembled stem and swivel block in the same plane.

12. A coupler with a stem having a pair of 5 rearwardly extending normally horizontal flanges, a swivel block with three forwardly extending flanges intercalated with said rearwardly extending flanges, said flanges having registering apertures, pivot means extending through said 10 apertures for connecting said swivel block and

stem, said stem forwardly of said flanges having upper, lower and side walls, portions of said upper wall extending from and substantially aligned with said upper horizontal stem flange, and other portions being upwardly convoluted to a height corresponding with that of the top surface of the upper flange of said swivel block, for maintaining the top surface of the assembled stem and block in the same plane.
